ROBERT CREUZBAUR, OF BROOKLYN, E. D., NEW YORK.

Letters Patent No. 103,990, dated June 7, 1870.

IMPROVEMENT IN LIQUID-METERS.

The Schedule referred to in these Letters Patent and making part of the same.

I, ROBERT CREUZBAUR, of the city of Brooklyn, E. D., in the county of Kings and State of New York, have invented certain Improvements in Fluid-Meters, of which the following is a specification.

Nature and Objects of the Invention.

The object of my invention is to produce a fluid-meter combining high efficiency and durability with ease of construction and low cost. This I claim to accomplish by the following means:

As to efficiency and durability—first, by passing the fluid through the meter by the shortest possible route, avoiding tortuous channels and the returning of the fluid upon its course; second, by balancing side pressures upon all moving parts in a simple manner, so as to obtain a minimum of friction and resistance.

As to ease of construction and low cost—first, by the use of such form, arrangement, and packing as gives to the body of the meter and to the main piston an advantageous shape for cheap manufacture, and which does away with the necessity of their being made of or lined with brass or other non-corrosive metals; second, by the arrangement herebelow described, which results in utilization of space and material, and avoids outside channels with their consequent difficult construction and waste of material.

Figure 1 is a longitudinal section, mostly vertical, through the line A A', fig. 3.

Figure 2 is a horizontal longitudinal section.

Figure 3 is a cross-section through B B', fig. 1.

Figure 4 is a cross-section through C C', fig. 1.

Figure 5 is a section across the pipe G and the valve H.

General Description.

The two parts D D, E E, bolted together through flanges d and e, form the outside shell, which is usually made of iron.

F is the piston, also made of iron.

Within the end D of the shell is the stationary pipe G, generally of brass, into which the ports g g, g¹ g¹, and passages g² g², fig. 2, are cut in pairs on opposite sides.

The pair of ports g g connect with the rear or left side of the piston F, and the pair g¹ g¹ connect with the front or right end of the said piston, and alternately they connect, through the inside of the valve H and its sleeve stem h¹, with the outlet-nozzle K, and also alternately with the inlet-nozzle J, through pipe G, and through the spaces h² between the said pipe and valve H, as indicated by the arrows.

The inlet-nozzle J, which is set into shell D by cast-

ing the latter around the same, serves for guide to the valve H, which slides upon its closed end J'.

The outlet-nozzle K is set in the same manner into cover L, and guides the sleeve-stem h¹, which slides within the same.

Attaching these nozzles to the ends of the meter gives the latter a more favorable position, by placing it in a direction coinciding with that of the pipes leading to and from the same.

The valve H plays over the ports g g and g¹ g¹ with its segmental parts h² h², figs. 2 and 5.

The open spaces h³ h³ between these parts lead into the sleeve-stem h¹.

Between these segmental parts h² h² the two outside open spaces h⁴, on opposite sides, figs. 1 and 5, carry the feed-fluid past the valve, so as to give it communication with ports g¹ g¹ and passages g² g².

The two pins h⁵, fig. 5, prevent the valve from turning.

The piston-valve M, which is firmly fastened upon the sleeve-stem h¹, has two ports, m', fig. 3, and slides within the piston-valve N.

That part of the sleeve h¹ which is inclosed by the piston-valve M is perforated, so that the fluid entering the piston M may escape through the sleeve h¹, as shown by the arrows.

The annular piston-valve N slides within cylinder P and upon piston-valve M.

This piston-valve N has also two ports, n¹, on opposite sides, and in positions at right angles to the ports m', as shown in fig. 3.

This piston N is fastened by a knob, n², to a rod, Q, fig. 1, which slides through the partition Q', and serves the purpose herebelow named.

This knob n² slides in slot p¹, of cylinder P.

The piston F is packed with rubber rolls R R', which cause the piston to move without leakage and without friction upon the inner surface of shell D and upon pipe G. These surfaces, as well as the piston itself, require no finish.

The piston-valve N is divided, around its circumference, into four parts, by the four ribs n², fig. 3.

The two opposite partitions thus formed, which embrace the two ports n¹, are in constant communication with the feed-fluid through the two opposite ports p² in cylinder P, which, through channels p³, connect with inlet-passages g² g² above named.

S S represent rubber or other abutments upon which the piston M cushions.

The operation of the meter is as follows:

Let the space between the valve and valve-stem H h¹ and the pipe G contain the feed-fluid, and the valve

H and its stem h^1 the escape-fluid. In the position shown in fig. 2, the feed enters through ports $g^2 g^3$ and presses upon the rear of the piston F, while the fluid in front of the piston escapes through ports $g^1 g^1$, and through the valve and its stem.

The feed-fluid also passes through passages $g^2 g^3, p^2$ and ports $n^1 n^1$, to the left of valve-pistons M N.

As the piston F moves to the right, the piston-valve N, then no longer held by the piston F through rod Q, and having escape-fluid on its right and feed-fluid on its left, can now advance to the right until the pistons N M stand over each other and close each others ports $n^1 m^1$. Thus they remain until the piston-valve N is carried past the piston-valve M by piston F, through rod Q, far enough to open the ports of M N on opposite sides.

The piston F having arrived at the end of its stroke, and slightly cushioned upon its rubber rolls R, the pressure of the fluid finds vent by directing its course upon piston M, while the piston N is held by rod Q, as shown in fig. 1. Piston M thus moves into or toward the position shown in fig. 1, taking the valve H with it, and thus reverses the ports for the main piston F.

Toward the other end of the stroke, piston F carries the rod Q by knob f'.

It is evident that with some slight modifications the course of the fluid may be reversed, with, however, an inferior result. It is also evident that any kind of a piston may be substituted for the piston F and its rubber rolls, with metal, leather, or any other packing, involving, however, increased cost and less efficiency.

The amount of fluid displaced by the main piston F and the auxiliary piston-valves M N constitutes the quantity measured and to be recorded by the counters. When a small stream is passed through a meter there is generally a considerable amount of leakage, particularly in unbalanced meters, which may be taken advantage of to obtain more fluid than the counters indicate. In this meter any attempt to benefit by such leakage is frustrated, because the pressure on all moving parts is balanced, keeping down friction, and because the auxiliary valve-pistons M N do not move to the end of their reach under a small stream, and thus decrease the amount passed through per revolution.

The counters receive motion from rod Q. As this rod, together with valve-piston N, does not travel to the end under a small stream, a special provision is necessary to give proper motion to the counters, arranged as follows:

The shaft 1 of ratchet-wheel 2, figs. 2 and 4, has an upper bearing in bushing 3, and a lower bearing in knob 4 4' cast onto cylinder P.

Leakage through the upper bearing is prevented by washer 5, ground to a true joint upon the bushing 3, and fitting loosely upon the shaft; and by rubber washer 6, which fits closely around the shaft, prevents the passage of fluid along the latter, and permits the washer 5 to accommodate itself to the face of the bushing 3 without reference to any obliquity in the shaft 1. The pressure of this rubber washer upon the shaft of the ratchet-wheel prevents the latter from returning on its path, and thus avoids the use of a check-dog for that purpose.

The arm 7 turns loosely upon the hub of the wheel 2, and has its slotted end supported by lever 8, the end pin 8' of which plays in that slot, and causes the arm 7 to turn.

This arm 7 carries a driver, 9, swinging loosely upon pin 7.

Lever 8 is pivoted in the aforesaid knob 4 4', and its slotted end, 8', is carried by a pin or knob, n'.

The result of this arrangement is that arm 7, with its driver, receives nearly all its motion while rod Q passes the central part of its full play, its motion near either end adding little to the motion of the arm. Thus, if rod Q should only move over one-third of its full path, the driver 9 would still have a greater reach than one tooth on the ratchet-wheel, while if rod Q travels its full stroke the driver will still have less reach than two teeth.

To support the counters and their cover, I use a loose plate, T, instead of forming the body of the meter into a shape to receive the same, thereby gaining labor and material.

The counter cover V I fasten on one side by the stud V', which enters lug t', and on the other side by a usual screw, W, a mode which saves time, labor, and material.

The drawing shows that the peculiar shape adopted for the part D of the shell adapts it to be cast on end, so as to form its own core, resulting in a true casting with a suitable surface for the rubber roll to travel upon.

The part E is also cast on end, with cores for channels p'. Its lip e' serves the double purpose of guide to piece D, as well as abutment to the ring R.

Claims.

1. The combination with the cylindrical shell D E of the end nozzles J and K, having their axis parallel to that of the shell, and of supply and exhaust-passages within the shell leading in a direction parallel to its axis, substantially as described.

2. The supply and exhaust-passages in a fluid-meter, passing centrally through the same in the direction of its long or major axis, as shown in the combination of the shell D E, nozzles J and K, and the passages H, h', and G G, substantially as described.

3. The combination of the cylinder P with annular valve-piston N and valve-piston M, and their ports, operating substantially as and for the purpose hereinbefore set forth.

4. The combination of a casing, G, and its ports, with the segmental valve H and its ports and passages, operating substantially as and for the purpose hereinbefore set forth.

5. The combination of shell D E and piston F with cylinder P, valve-pistons M and N, sleeve G, valve H, and their ports and passages, substantially as and for the purpose hereinbefore set forth.

6. The loose counter supporting-plate T, placed tangentially to the circumference or sides of the meter-shell, in combination with the bushing-box 3 and shaft 1, substantially as described.

7. The combination with a ratchet-wheel, 2, and a driver-carrying arm, 7, in a fluid-meter, of a motion-transmitting lever, 8, substantially as and for the purpose hereinbefore set forth.

8. The combination with a piston, F, packed with one or more rubber rolls, R, of a meter-cylinder or shell formed of two parts, D and E, when the latter are so joined that the lip e' serves as a retaining-ring to rubber roll R, substantially as and for the purpose hereinbefore set forth.
